(57) **CLAIM**

The ornamental design for a capsule with logo, as shown and described.

DESCRIPTION

FIG. 1 is a top perspective view of a capsule with logo showing my new design;

FIG. 2 is a bottom perspective view thereof;

FIG. 3 is a front view thereof;

FIG. 4 is a left side view thereof, the claimed portion visible in the right side view being a mirror image thereof;

FIG. 5 is a rear view thereof;

FIG. 6 is a top view thereof; and,

FIG. 7 is a bottom view thereof.

The dashed broken lines represent elements of the capsule and environment that form no part of the claimed design. The shorter dashed broken lines represent a perforation that forms no part of the claimed design.

1 Claim, 2 Drawing Sheets# US D769,726 S
